(57) CLAIM

The ornamental design for a document preparation station, as shown and described.

DESCRIPTION

FIG. 1 is a perspective view, from the front and above, of a document preparation station in a first configuration according to my new design;

FIG. 2 is a perspective view thereof, from the rear and above, in the first configuration;

FIG. 3 is a perspective view thereof from the front and above in a second configuration with the terminal shown removed from the housing;

FIG. 4 is a right-side elevational view thereof in the first configuration, the undisclosed left side is a mirror image;

FIG. 5 is a top plan view thereof, in the first configuration; and,

FIG. 6 is a front elevational view thereof, in the first configuration.

The station includes a main housing containing a printer and control unit and a data entry terminal.
